UNITED STATES PATENT OFFICE.

LEONARD M. LANNING, OF WALLA WALLA, WASHINGTON.

PIPE-LOCK.

1,359,900.

Specification of Letters Patent. Patented Nov. 23, 1920.

Application filed January 22, 1920. Serial No. 353,178.

To all whom it may concern:

Be it known that I, LEONARD M. LANNING, a citizen of the United States, residing at Walla Walla, in the county of Walla Walla, 5 and State of Washington, have invented certain new and useful Improvements in Pipe- Locks, of which the following is a specification.

This invention relates to pipe locks and 10 has for its objects to provide a simple, inexpensive and highly efficient means for securing pipes.

A further object is to provide a means that 15 has relatively few parts and with slight interchanges may be adapted to lock the joints thereof together and to lock a pipe in its ultimate position, as in a flue.

A further object is to provide a means which 20 yieldingly locks in a manner to provide compensation for expansion and contraction due to varying temperatures.

With these and other objects in view reference is had to the accompanying drawings in which—

25 Figure 1 shows the application of the device on a pipe inserted into a large opening;

Fig. 2 shows the pipe inserted into an opening of correct size;

Fig. 3 is a plan view of a modified form of 30 draw bar; Fig. 3^a is a sectional view of the modified form of drawbar;

Fig. 4 shows a string of pipe supported from below;

Fig. 5 shows the device attached to the interior of the pipe;

Fig. 6 shows an end elevation of the drawbar;

Fig. 7 shows a side elevation of the drawbar;

40 Fig. 8 is a plan view of the draw bar;

Fig. 9 is a side elevation of the spring lock; and

Fig. 10 is a plan view of the spring lock.

In the drawings like numerals refer to like 45 parts throughout and the numeral 1 refers to the pipe which, as shown in the drawings is represented as stove pipe although it must be understood that the device is equally applicable to any suspended pipe.

50 2 represents a section of flue having the usual opening 3 into which the pipe is to be locked by means of the draw bar 4 and the lock 5.

The draw bar consists of a hook portion 6 55 and a shank portion 7, the shank portion being bent as at 8 Fig. 7 to produce a snug

seating of the projected end of the shank against the outer perimeter of the pipe.

The draw bar contains a series of apertures 9 longitudinally disposed in the shank into 60 which a latch, to be described, seats for the locking purpose.

In the end of the shank barbs 10 are provided which are intended to engage the edge 11 of the slot 12 through which the shank 65 projects, to prevent accidental removal of the drawbar while placing or removing the pipe.

A guide member 13 is attached to the inner side of the pipe and slidably mounts the 70 draw bar 4 and is positioned in the pipe in a manner to cover the slot 12 to prevent a smoke leak therethrough.

Attached to the pipe, and positioned thereon to cooperatively engage the draw bar, is 75 the lock 5 consisting of a plate 14 which carries lugs 15 which in turn bear the crank arm 16 journaled therein. A tongue 17 is journaled on the crank arm and engages a spring 18 which is interposed between the tongue 80 and the latch 19, the latch having a bent end 20 which seats into the aforementioned apertures 9 of the draw bar.

It will be noted by reference to Fig. 9 that the crank arm 16 is journaled in the lugs 15 85 off center so that when the tongue 17 is brought down to the locked position there will be no danger of the accidental unlocking of the device.

Fig. 3 shows a modified form of draw bar 90 7^a for use on the pipe directly in which case the pipe, to which the draw bar is attached, becomes in a manner the sliding member of the draw bar, the pipe being drawn upon the adjoining pipe by means of the lock. 95

This lock, through the medium of the spring, provides a yielding pressure on the draw bar and thus as the expansion and contraction occurs, due to the varying temperature, the pull remains constant and the 100 joint is constantly maintained in its tightest position.

It is shown by reference to Figs. 1 and 2 that the hook portion 6 of the draw bar is of sufficient length to engage the inner 105 wall of the flue whether the hole 3 is or is not of the proper size, thus regardless of the size of the hole a secure lock is obtained thereon.

In the case of long strings of pipe as 110 shown in Fig. 4 the lock will be placed beneath the pipe thus forming a suspension

5 joint of sufficient strength to maintain a rigid string; and as shown in Fig. 5 the lock may be installed within the pipe with equal efficiency; in this case however the slot 12 will be omitted and the guide member 10 may also have the slight modification shown in Fig. 5.

10 In use the lock 5 and the draw bar 7 is riveted or otherwise fastened to the pipe previous to erection, and the draw bar 7 is placed in the guide member, the barb 10 snapping past the edge 11 of the slot 12. The flue joint is now inserted and locked in place and the collar 21 brought to position 15 against the wall of the chimney. The elbow 22 (or next joint) is now applied and locked and thus throughout the assembling a joint is added and locked until the work is completed.

20 In the case of the locks being within the pipe the locking is accomplished by inserting the arm and performing the locking operation therein.

25 Having thus described my invention, I claim—

1. In a pipe lock, a draw bar, and a lock composed of a plate, lugs extending upward from said plate, a crank arm pivotally mounted in said lugs, a tongue journaled 30 on said crank arm and engaging a spring, a latch, a spring interposed between said tongue and said latch, said lock attached to the pipe and positioned thereon to coöperatingly engage said draw bar.

35 2. In a pipe lock, a draw bar, said draw bar consisting of a hook portion and a shank

portion, a guide member attached to said pipe and slidably mounting said draw bar, and a lock composed of a plate, lugs extending upward from said plate, a crank arm 40 pivotally mounted on said lugs, a tongue journaled in said crank arm and engaging a spring, a latch, a spring interposed between said tongue and said latch, said lock attached to the pipe and positioned thereon to 45 coöperatingly engage said draw bar.

3. In a pipe lock, a draw bar, said draw bar consisting of a hook portion and a shank portion, a guide member attached to said pipe and slidably mounting said draw bar, 50 a slot in said pipe through which said shank portion projects, said guide member being positioned in said pipe to cover said slot, and a lock attached to the pipe and positioned thereon to coöperatingly engage said 55 draw bar.

4. In a pipe lock, a draw bar, said draw bar consisting of a hook portion and a shank portion, said shank portion being provided with a series of apertures longitudinally 60 disposed therein and carrying a barb on the outer end thereof, a guide member attached to said pipe and slidably mounting said draw bar, a slot in said pipe through which said shank portion projects, said guide 65 member positioned in said pipe to cover said slot, and a lock attached to the pipe and positioned thereon to coöperatingly engage said draw bar.

In testimony whereof I affix my signature. 70

LEONARD M. LANNING.
